IMPROVED TOBACCO PRODUCT

Werner Pettersson, Berlin, Germany

No Drawing. Application May 1, 1929, Serial No. 359,717, and in Germany July 22, 1927. Renewed July 19, 1933

2 Claims. (Cl. 131—31)

This invention relates to an improved tobacco product.

Tobacco has heretofore been treated by the addition thereto of various substances, such as perfume, medicaments and the like to give to the tobacco when it is utilized, as in smoking, the particular flavor or aroma of the added substance.

It is the object of the present invention to provide an improved treated tobacco by impregnating the tobacco with a substance which will have no chemical reaction with the elements of the tobacco, and which substance is adapted to be converted into a volatile state and in said state dissipated and mixed with the smoke of the tobacco as the tobacco is burned, as by smoking, to serve as a counterant to neutralize the properties of the smoke which cause irritation of the mucous membranes, and effect the neutralization of the irritant in the tobacco smoke without in any way changing or impairing the natural condition and taste or aroma of the tobacco.

Other objects and advantages of the invention will become apparent as the description proceeds.

It is well known that tobacco smoke exerts on the mucous membranes an irritating action frequently leading to coughing, this being the primary symptom of an abnormal condition of the mucous membranes. The mucous membranes of the lungs have the task of performing resorption during breathing, and of allowing their biological defensive powers to enter into activity should danger threaten from any morbific agent. The irritation to which the mucous membranes are constantly subjected by reason of tobacco smoke accordingly produces a deleterious and harmful effect on the membranes, that is to say—as regards their biological task which the membranes are called upon to fulfill and the protective action they are required to perform, so that they are susceptible to infection and the spreading of illness or disease, such as bronchitis, tuberculosis, etc.

Accordingly, therefore, to the invention, the tobacco is treated with a material which, when the tobacco burns, and produces smoke, is converted into volatile form and acts in opposition or as a counterant to the irritation arising from the tobacco smoke, and without in any way whatever affecting the flavor or the aroma of the tobacco.

This material is converted into and dissipated in a volatile state by the burning of the tobacco, in which state it mixes with the smoke of the tobacco and serves as a counterant to neutralize

the properties of the tobacco smoke which cause irritation of the membranes. Substances having the properties to produce the desired result comprise carbon-hydrogen-nitrogen compounds or acridinium salts, coal tar derivatives, such as 3,6 diamino 10 methyl-acridinium-chloride, whose formula is:

65

ethoxydiamino acridinium-hydrochloride or orthoxychinolin potassium sulphate, whose respective formulae are:

70

75

said substances having the properties that they will not cause irritation of the mucous membrane and are also strong disinfectants. Previous to utilizing the tobacco in making a smoking product, such as cigarettes, the tobacco is treated by impregnating it by spraying the tobacco with said substance in solution in water to distribute the same evenly over the tobacco, which spraying is effected by subjecting the tobacco to an elevated temperature to render the tobacco highly absorptive. To effect the treatment of the tobacco it is placed on a sieve-like conveying band, above which is situated a spraying apparatus filled with a watery solution of diamino methyl-acridiniumchloride. The solution passes out of the spraying apparatus in the form of a mist or vapor, and is distributed evenly over the tobacco transported by the conveyor band.

The conveyor band at the point situated below the spraying apparatus is preferably given a joggling motion, so that the tobacco will be caused to turn and will be acted upon on all sides with the spray. Underneath the band and preferably at a point situated below the spraying apparatus to produce an elevated temperature may be provided a dry heat apparatus with the object of increasing the absorptive capacity of the tobacco.

100 grammes of a 1% solution of diamino methyl-acridiniumchloride will be sufficient for 110

the treatment of approximately 300 grammes tobacco. One cigarette with the tobacco treated in this manner will accordingly contain approximately .0033 of a gram of diamino methyl-acridiniumchloride.

In smoking a tobacco product the tobacco of which has been treated in the manner stated, the substance in question, for example the diamino methyl-acridiniumchloride, will, as the smoke is formed by burning the tobacco, simultaneously be converted either wholly or in part into a tasteless volatile form, and pass together with the smoke to the mucous membranes. The smoke, therefore, without the flavour or aroma thereof being in any way impaired, will not have any injurious action on the natural function of the membranes.

It will be understood that no restriction is

made to the exact method as described, nor to the particular proportion employed, nor do I wish to limit myself to the substances which have been set forth merely by way of example, or to the particular apparatus for carrying out the treatment, as various modifications may be made within the scope of the appended claims without departing from the spirit of the invention.

What I claim as new and desire to secure by Letters Patent is:

1. As a new article of manufacture, tobacco impregnated with 3.6 diamino 10 methyl-acridiniumchloride.
2. As a new article of manufacture, tobacco impregnated with diamino methyl-acridiniumchloride.

WERNER PETTERSSON.
